UNITED STATES PATENT OFFICE.

ROBERT S. BOLGER, OF RICHMOND HILL, NEW YORK.

PAPER BARREL AND METHOD OF MANUFACTURING THE SAME.

Application filed July 14, 1919. Serial No. 310,783.

To all whom it may concern:

Be it known that I, ROBERT S. BOLGER, a citizen of the United States, residing at Richmond Hill, in the county of Queens 5 and State of New York, have invented new and useful Improvements in Paper Barrels and Methods of Manufacturing the Same, of which the following is a specification.

My invention relates to bilged barrels 10 and the method of manufacturing or producing the same. The object of my invention is to produce a barrel of bilged formation, or in other words a barrel the ends of which are of less diameter than the 15 medial portion thereof and the body wall of which is composed of strips of sheet material assembled in such relation to each other and connected in such manner as to form a commercially practical, strong and 20 imperforate barrel adapted for the storage and shipment of produce in general.

Another object in view is to produce such a barrel economically both as regards the material used and the class of labor required, to the end that the barrels may be placed on the market at less cost than the 25 type of barrel now in common use, requiring staves or hoops.

Another object in view is to produce a 30 barrel head of cheap and efficient construction having the requisite factors of strength and lightness for the amount of material used; also to provide a cheap and practical means for securing such head in the barrel 35 body.

The invention consists in the barrel construction and method of production of the same herein fully described, illustrated and claimed.

40 In the accompanying drawings;—

Fig. 1 is a side elevation of a tube composed of spirally wound strips of sheet material such as paper adhesively united, before the adhesive has set.

45 Fig. 2 is a similar view of the same after the tube has been deformed into bilged formation.

Fig. 3 is a section on the line 3—3 of Fig. 1, looking in the direction of the arrows.

50 Fig. 4 is a section on the line 4—4 Fig. 2, looking in the direction of the arrows.

Figs. 5, 6, 7, and 8 are views respectively

corresponding with Figs. 1, 2, 3, and 4 showing another way of arranging the body forming strips. 55

Fig. 9 is a section on the line 9—9 of Fig. 10, looking in the direction of the arrows, showing a type of machine adapted to be used in producing the barrel, and also showing the barrel tube in place before the 60 bilging operation.

Fig. 10 is a section on the line 10—10 of Fig. 9, looking in the direction of the arrows.

Fig. 11 is a section on the line 11—11 of Fig. 12, after the bilging operation. 65

Fig. 12 is a section on the line 12—12 of Fig. 11, looking in the direction of the arrows.

Fig. 13 is a section on the line 13—13 of Fig. 14, looking in the direction of the arrows, after the bilging pressure is released and the barrel is ready to be removed from the machine. 70

Fig. 14 is a section on the line 14—14 of Fig. 13, looking in the direction of the arrows, showing the sections of the outer form opened to admit of the removal of the barrel body. 75

Fig. 15 is a fragmentary diametrical section showing a barrel head, the relation thereof to the barrel body, and the preferred means for holding the barrel head in place. 80

Fig. 16 is a broken perspective view of the barrel head shown in Fig. 15. 85

Fig. 17 is a plan view showing the manner of producing the barrel head-forming sections from a strip of sheet material.

Fig. 18 is a fragmentary diametrical section, showing the end portion of the barrel before the barrel head and outer retaining ring are inserted. 90

Fig. 19 is a plan view of the head shown in Figs. 15 and 16.

Figs. 20, 21, 22, and 23 are diametrical sections of barrel heads of modified formation. 95

Fig. 24 is a diametrical section, showing a modified form of retaining ring.

Fig. 25 is a plan view of one of the head retaining rings. 100

The barrel body is made up of strips of sheet material, preferably consisting of dry, finished paper of suitable density or hard-

ness to produce a tough and commercially satisfactory main barrel body wall, when said strips have been properly assembled and united together as hereinafter explained. In this first step of production, as long a tube (hollow cylinder) as practicable is made and cut in sections each of suitable length to form one barrel body, such length being greater than the length of completed article in order to allow for longitudinal contraction of the tube while undergoing the bilging operation hereafter described.

The strips 1 are preferably assembled by a suitable winding machine so that they will extend spirally with respect to the major axis of the barrel tube as shown in Figs. 1 and 2 as such method results in a stronger barrel wall. The strips 1 may however extend longitudinally of the barrel body wall as shown in Figs. 5 and 6. In both instances an imperforate main barrel body wall is obtained.

The body-forming strips 1 are furthermore assembled with their lateral portions overlapping each other as shown in Figs. 1 to 8, both inclusive, and are united together in such relation by a suitable adhesive. A slowly drying adhesive is preferably used for such purpose to allow ample time for the bilging operation which follows.

The bilging of the barrel tube may be performed on a machine such as is illustrated in Figs. 9 to 14, both inclusive, to distort the barrel tube shown in Fig. 1, for example, into bilged formation as shown, for example, in Fig. 2. The machine shown, comprises a base A, forming a support for outer and inner forms B and C between which the wall of the barrel tube is confined during the bilging operation. The outer form is of sectional construction and embodies separable halves connected at the bottom by one or more hinge pins D in order that the sections of the form B may be opened or moved apart as shown in Fig. 14 to permit the finished barrel body to be removed from the machine. The sections of form B are secured together at their free edges by any suitable clamping or fastening means indicated at E. The internal shape of the sections of the form B corresponds with the bilged external shape of the finished barrel body as shown in Figs. 9 and 11. At one end of the machine there is a fixed stop or annular abutment F preferably consisting of an integral part of the machine frame or base A. During the bilging operation, one end of the barrel tube rests against said fixed stop, the position of said tube being thus gaged.

The inner form or core of the machine, in the illustrated embodiment thereof is expandable and collapsible and comprises a hollow cylindrical fixed member G having openings H therein, and also having a fluid

inlet connection or pipe I in the head J thereof, the same being controlled by a valve or stop cock K.

The core member G at the ends thereof has annular flanges L forming spaced seats for the end portions of a resilient flexible sleeve or tube M constituting the inner form, proper. One end of said sleeve or tube is held between the fixed stop F and the adjacent flange L of the member G. The other end of said sleeve or tube M may extend beyond the other flange L and be held against the head N at that end of the member G and a clamp O in the form of a disk secured to said head by fastening means P. Normally the sleeve or tube M assumes a true cylindrical condition as shown in Figs. 9 and 13, but is adapted to assume the bilged shape of Fig. 11 when fluid (air or liquid) is admitted to the fluid pressure chamber formed within and by the fixed and resilient members C and M of the core or inner form G.

A barrel tube preferably such as shown in Figs. 1 and 5 is placed over the free end of the inner form G and over the expandable sleeve or tube M, as shown in Fig. 9. The sections of the outer form B are then closed and fastened as in Fig. 10. Valve K is then opened and the fluid under pressure fills the fluid pressure chamber passing through the openings H, expanding the sleeve M and pressing the wall of the barrel tube firmly against the inside wall of the outer form B, the laminations of which are still free to change their relative positions due to the fact that the adhesive is still in a moist or unset condition. The pressure may be maintained until the setting of the adhesive has reached any desired stage or until it has completely set. The pressure is then released, permitting the sleeve or tube M to reassume its normal condition. Then the sections of the outer form are unfastened and opened and the barrel body (now bilged) is removed from the machine. The above described operation is repeated for each barrel body. The operation is the same on both of the barrel tubes shown in Figs. 1 and 5, or other forms of tubes to be expanded.

At some time subsequent to the bilging operation above described, the inner head retaining rings 8 which have previously been made are placed in position and adhesively or otherwise held in place at the proper distances from the ends of the barrel. One head is then inserted and an outer head retaining ring 9 is then placed in position and fastened by adhesive or other means to permanently secure said head. The other head and its outer retaining ring will ordinarily be applied by the consumer.

The head shown in Figs. 15 and 16 is made up of a number of disks 3 and rings 130

4 punched out of sheet material such as strips 5 of paper as indicated in Fig. 17, smaller disks may be punched from the centers of larger disks to form the rings. In 5 this way disks and rings of any desired size or diameter are obtained, the dimensions thereof varying accordingly.

In the preferred form of barrel head shown in Figs. 15 and 16 two disks 3 of 10 one size are employed, and rings 4 of larger diameter are interposed between said disks, four of such rings being used, two of the same internal diameter and two of another internal diameter, smaller spacing disks 6, 15 formed in the same way, are placed centrally between the disks 3, and other reinforcing disks 7 of smaller size than the disks 3 are placed upon the latter. All of said 20 disks and rings are united by an adhesive or other means.

The inner and outer head retaining rings 8 and 9 respectively are each made up of a strip of sheet material, such as paper, wound or wrapped upon itself until the necessary 25 thickness of wall is obtained as in Figs. 15, 18, 24 and 25. Such ring may be given a beveled or chamfered shape by using a tapering strip of material as in Fig. 24. The 30 laminations are preferably united by an adhesive.

In Fig. 20 the barrel head embodies outer disks 10 between which are placed larger disks 11, rings 12 being placed between the disks 11 and central spacing disks 13 being 35 also used. In Fig. 21 the head is shown as comprising a single large disk 14, a ring 15 of the same diameter, a spacing ring 16 between them, a plurality of central spacing disks 17, and disks 18 and 19 of different 40 diameters applied to the ring 15. The arrangement in Fig. 22 is similar to that in Fig. 21, two rings 16' being used instead of the one ring 16 and two disks 19' being used in place of the one disk 19. Three spacing 45 disks 17' are also used instead of the two disks 17. The arrangement shown in Fig. 23 embodies the same elements shown in Figs. 15 and 16 except that the rings 4' are formed with annular offsets 20 which serve 50 to reinforce or strengthen the outer edge portion of the head and also form the equivalent of gaskets when confined between the retaining rings 8 and 9. It is to be understood that a barrel head of any thickness 55 may be built up of disks and rings to produce a strong and lightweight structure.

Any space remaining between the barrel head and the retaining rings therefor and the inside surface of the main wall of the 60 barrel may be filled with any sealing medium to obtain a tighter package. The barrel bodies and heads may of course, be made in various sizes to suit the manufacturer and consumer.

I claim—

1. A barrel having an imperforate bilged body comprising superimposed overlapping layers adhesively united and each composed of strips extending longitudinally of the body.

2. A barrel having an imperforate bilged body comprising superimposed overlapping layers adhesively united and each composed of strips extending in the general direction of length of the body.

3. A barrel having an imperforate bilged body comprising superimposed overlapping layers adhesively united and each composed of strips the lateral edges of which touch each other at the ends of the body and the intermediate portions of which edges are in spaced relation to each other.

4. A barrel having a bilged imperforate body composed of adhesively united overlapping strips of sheet material extending longitudinally of the body and primarily separate barrel-head-retaining rings adhesively united to the inside surface of such body.

5. A barrel having a bilged imperforate body composed of adhesively united overlapping strips of sheet material extending longitudinally of the body, a barrel head, and primarily separate barrel-head-retaining rings at opposite sides of said head extending transversely of said strips and adhesively 95 united to the inside surfaces thereof.

6. A barrel having a bilged imperforate body composed of adhesively united overlapping strips of sheet material extending longitudinally of the body, a barrel head, and primarily separate barrel head-retaining rings at opposite sides of said head, one of said rings extending transversely of and being adhesively united to the body forming strips, and the other ring being adapted to 100 be disposed and united in the same manner.

7. A barrel having a bilged imperforate body composed of adhesively united overlapping strips of sheet material, a barrel head, and a barrel-head-retaining ring 110 formed of a strip of sheet material wound upon itself in laminated formation and extending transversely of the body forming strips and adhesively united thereto.

8. A barrel head composed of imperforate disks arranged in spaced relation to each other, and an annular spacing member interposed between said disks and united thereto by an adhesive.

9. A barrel head composed of imperforate 120 disks in spaced relation to each other, and an annular spacing member between and of less superficial area than said disks, said parts being adhesively united.

10. A barrel head composed of imperforate disks in spaced relation to each other, and a plurality of spacing members interposed in a common plane between said disks,

the combined superficial area of said spacing members being less than the superficial area of the disks, all of said parts being united by an adhesive.

5 11. A barrel head composed of imperforate disks in spaced relation to each other, an annular spacing member between said

disks, and a central disk shaped spacing member between said disks in the same plane with the annular spacing member, all of said parts being united.

In testimony whereof I affix my signature.

ROBERT S. BOLGER.
